UNITED STATES PATENT OFFICE.

HAROLD F. SHEPHERD, OF RENO, NEVADA.

APPARATUS FOR DELIVERING MEASURED CHARGES OF FLUID.

Application filed October 28, 1922. Serial No. 597,510.

To all whom it may concern:

Be it known that I, HAROLD F. SHEPHERD, a citizen of the United States, residing at Reno, in the county of Washoe and State of Nevada, have invented new and useful Improvements in an Apparatus for Delivering Measured Charges of Fluid, of which the following is a specification.

This invention is designed to deliver measured charges and is particularly advantageous in connection with fuel pump systems of explosive engines. Such an exemplification of the invention is hereby specifically described and illustrated.

Fuel pump systems designed for internal combustion engines are ordinarily equipped with a pump unit for each cylinder and each pump unit is provided with a separate adjustable connection to the governor. This is necessary on account of the tendency of the pumps to deliver slightly different quantities of the fuel according to their condition or individual peculiarities of workmanship and performance. The need of these individual 20 adjustments for each pump unit introduces the possibility of mis-adjustment and a considerable degree of skill is required to so adjust the pumps that each cylinder receives the same quantity of oil and that the governor mechanism has the freedom of its entire 30 range. One of the principal objects of this invention is to obviate this difficulty.

In the apparatus the delivery of fuel is divided into two functions. The fuel is measured with a measuring instrument, or pump, and delivered to force pumps, one for each cylinder. In the apparatus a single measuring device is utilized and by controlling this measuring device the fuel delivery to each cylinder is controlled.

The apparatus is illustrated in the accompanying drawings as follows:

Fig. 1 shows a side elevation of an explosive engine, partly in section.

Fig. 2 a section of one of the force pumps of the engine.

Fig. 3 a side elevation of the cam mechanism actuating the force pump.

Fig. 4 a section on the line 4—4 in Fig. 2.

Fig. 5 a central section of the measuring pump.

Fig. 6 a section on the line 6—6 in Fig. 5.

1 marks the engine base, 2 the engine cylinders, and 3 the fuel inlet pipes of the cylinder. The inlet pipe to the cylinder is carried into a fitting 4. Each pump has a

discharge valve fitting 5 clamped between the fitting 4 and the force pump body 6. The body has a plunger cylinder 7 in which is arranged a pump plunger 8. The plunger has a conical head 9 which operates against a seat 10 in the upper end of the cylinder and forms a stop limiting the downward movement of the plunger. A collar 11 is secured to the lower end of the plunger by means of a ring 12 arranged in a groove 13. A spring 14 operates against the collar 11 and gives the plunger its return stroke. A lift 15 has a guide 16 operating on the collar 11 and is pivoted at its lower end on a yoke 16^a which is carried by a rocker 17. The rocker has a cam roller 18 which operates on a cam 19, the cam 19 being mounted on a cam shaft 20 of the engine. The cam shaft has a cam lift 21 which forces the plunger upwardly to force a charge of fuel into a cylinder. A discharge valve 22 prevents a return flow from the pipe 3 and an inlet valve 23 prevents a return flow from the pump in the forcing stroke. These valves operate in the usual manner of valves in pumps. A test valve 24 is provided and the drainage past the plunger is caught by the guide 16 and the valve 24 and guide 16 discharge through pipes 25 and 26 to a drip catch 27.

Fuel is drawn into the cylinder 7 by way of an opening 28 and the valve 24 leads from an opening 29. These openings extend through the seat 10 and are positively closed by the tapered end 9 of the plunger, the purpose of this being to close off each force pump from the fuel system so that a charge intended for one pump will be cut off from the other pumps. The cam 21 has a dwell or extension 30 which holds the tapered end 9 slightly open after the forcing action and after a return movement of the plunger down to the slightly open position. During this dwell the measured charge is delivered to the pump chamber and immediately thereafter the roller 18 moves off the extension 30 permitting the tapered end 9 to positively close the opening 28 and all communication to the measuring system.

The measuring pump is driven from the cam shaft 20 through a cam 31, the cam being provided with a number of lifts 32 corresponding to the number of cylinders. The cam operates on a roller 33 mounted on a rocker 34, the rocker being mounted on the base of the engine. The rocker op-

erates a pump plunger 35 through an adjustable push pin 36. The plunger operates in a liner 37 arranged in an opening 38 in a body 39. The body 39 is carried by 5 stanchions 40 extending from the base. A fuel pipe 41 extends into a passage 42 and passages 43 extend from the passage 42 to the top of the liner and a seat 44. An inlet valve in the form of a ring 45 operates 10 on the seat 44. It will be noted that the inlet valve surrounds the plunger and that a flange 46 on the plunger engages the valve and closes the valve at the end of the suction stroke of the plunger. The flange is 15 notched at 47 so as to give an overflow of fluid. A return movement of the plunger is forced by a spring 48. A discharge valve 49 is carried by a discharge valve plug 50 which is seated on the liner 37. A closure 20 plate 51 is seated against the plug 50 and forms a means of communication with a discharge passage 52. The discharge passage leads to a bypass chamber 53 from which a pipe 54 leads to the inlet valve 23 of 25 the force pumps. A bypass valve 55 operates on a seat 56 in a plug 57 in the bottom of the chamber 53. A spring 58 seats the valve. A chamber 59 communicates with a passage 60 controlled by the bypass valve 30 and a passage 61 returns the fluid bypassed to the inlet passage 42. A plunger 62 operates to open the bypass valve. The plunger is carried in an equalizing lever 63, one end of which is connected by a link 64 35 with the rocker 34. The opposite end of the lever is fulcrumed on a link 65 extending from a lever 66; this lever being controlled by a governor 67 of ordinary form and driven by the engine.

40 In the operation of the measuring device a full charge is drawn into the pump chamber on the downward stroke of the plunger. On the forced stroke of the plunger the charge is delivered by the pump through 45 the system of passages to the force pump having the passage 10 open, the lifts 32 of the cam being timed with the extension 30 to effect this result. This charge is modified by the well-known bypass method. As 50 soon as the bypass is opened some, or all, the movement to the pump chamber ceases

and the balance is bypassed through the bypass valve. The movement or opening of the bypass is varied by the governor changing the fulcrum of the lever 63. 55

What I claim as new is:

1. In a charge delivering device, the combination of a plurality of pumps; plungers in said pumps having tapered ends; seats containing the inlets to the pumps closed by 60 said tapered ends; a measuring device common to said pumps; and a cam device actuating the plungers holding the tapered ends off its seat during the charging movement and closing the tapered ends on the seat 65 during the charging movement of the other pumps.

2. In a charge delivering device for explosive engines, the combination of a plurality of cylinders; a forced pump for each 70 cylinder comprising a plunger having a tapered end thereon; a seat operating on the tapered end containing the inlet to the pump; a cam device actuating the plunger and holding the same in an intermediate 75 position to receive a charge; a measuring instrument common to said pumps comprising a plunger; an inlet valve around the plunger seated by the movement of the plunger on its suction stroke; a bypass for 80 varying the measured charge; and means controlling the bypass.

3. In a charge delivering device for explosive engines; the combination of a plurality of cylinders; a forced pump for each 85 cylinder comprising a plunger having a tapered end thereon; a seat operating on the tapered end containing the inlet to the pump; a cam device actuating the plunger and holding the same in an intermediate 90 position to receive a charge; a measuring instrument common to said pumps comprising a plunger; an inlet valve around the plunger seated by the movement of the plunger on its suction stroke; a bypass for 95 varying the measured charge; and means controlling the bypass comprising a governor responsive to speed.

In testimony whereof I have hereunto set my hand:

HAROLD F. SHEPHERD.
